No. 37,118.

Patented September 6, 1904.

UNITED STATES PATENT OFFICE.

PAULDING FARNHAM, OF GREATNECK, NEW YORK.

DESIGN FOR A HANDLE FOR SPOONS, FORKS, OR SIMILAR ARTICLES.

SPECIFICATION forming part of Design No. 37,118, dated September 6, 1904.

Application filed August 9, 1904. Serial No. 220,146. Term of patent 7 years.

To all whom it may concern:

Be it known that I, PAULDING FARNHAM, a citizen of the United States, residing at Great-neck, Nassau county, in the State of New York, 5 have invented a new, original, and ornamental Design for a Handle for Spoons, Forks, or Similar Articles, of which the following is a specification, reference being had to the accompanying drawing, forming part thereof, 10 and showing a view representing the obverse

side of a handle for a spoon, fork, or similar article incorporating my said design.

What I claim is—

The ornamental design for a handle for a spoon fork or similar article, substantially as 15 shown.

PAULDING FARNHAM.
